UNITED STATES PATENT OFFICE.

EUNICE E. CHAPMAN, OF PETERSBURG, TENNESSEE.

CHURN.

1,104,627.

Specification of Letters Patent. Patented July 21, 1914.

Application filed March 19, 1914. Serial No. 825,903.

To all whom it may concern:

Be it known that I, EUNICE E. CHAPMAN, a citizen of the United States, residing at Petersburg, in the county of Lincoln and 5 State of Tennessee, have invented certain new and useful Improvements in Churns; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in churns and the object in view is to produce a simple and efficient apparatus of this nature comprising a rotary dasher, adjustable to adapt the same for 20 various sized receptacles and having wings so arranged that an upward violent agitation may be given the cream.

The invention comprises various details of construction and combinations and arrangements of parts which will be herein-after fully described, shown in the accompanying drawings and then specifically defined in the appended claim.

I illustrate my invention in the accompanying drawings, in which:

Figure 1 is a perspective view of my improved churn. Fig. 2 is a side elevation. Fig. 3 is a rear elevation, and Fig. 4 is a perspective view of a part of the invention.

35 Reference now being had to the details of the drawings by letter, A designates a churn body or receptacle mounted upon the base B.

E is a standard rising from the base and 40 having braces C. Said standard is provided with a slot F near its upper end and a cap F' is fitted over the slotted top of the standard. A hanger, designated by letter H, is movable within said slot and designed 45 to be held in an adjusted position by means of a cam lever K. Said hanger has arms L

in which the worm shaft N is journaled, having a socket N' at its lower end adapted to receive the dasher shaft O, which latter is held in place by means of the thumb screw 50 P. The hanger is provided with a yoke R, the arms of which have journaled therein a crank shaft S and to which a worm wheel T is fixed and which is in gear with the worm shaft N. The wings W at the lower end of 55 the dasher are so positioned that, when the dasher is rotating, an upward current will be caused to the cream, throwing it violently against the upper portion of the receptacle, thus thoroughly agitating the same 60 in the churning process.

By the provision of a hanger made as shown and described, it will be noted that the same may be raised and lowered to adapt the dasher to rotate at different elevations as may be desired, the parts being held in adjusted positions by means of the cam levers as shown.

What I claim to be new is:

A churn comprising a support having a 70 vertical slot therein, a hanger with a shank portion extending through and movable within said slot, a forked cam member pivoted to the end of said shank portion and straddling the projecting end thereof and 75 adapted to engage said standard on either side of the slot, said hanger having curved arms extending in pairs at right angles to each other and having apertures in the ends forming bearings, a dasher driving shaft 80 journaled in the bearings in the ends of one set of arms and a driving shaft journaled in the other arms, a wheel upon the driving shaft and having gear connection with the dasher driving shaft, as set forth. 85

In testimony whereof I hereunto affix my signature in presence of two witnesses.

EUNICE E. CHAPMAN.

Witnesses:

O. F. GILL,
G. P. GLOTHANY.
